Kamble, S. et al., "Thrust Bearing Assembly for Engine Crankcase," U.S. Appl. No. 16/634,397, filed Aug. 7, 2019, 30 pages.

Primary Examiner — Ania Aman

(74) Attorney, Agent, or Firm — McCoy Russell LLP

(57) **CLAIM**

The ornamental design for a bearing apparatus, as shown and described.

DESCRIPTION

FIG. 1 is a front-right perspective view of a bearing apparatus according to the claimed design.

FIG. 2 is a front view of the bearing apparatus.

FIG. 3 is a rear view of the bearing apparatus.

FIG. 4 is a right side view of the bearing apparatus.

FIG. 5 is a left side view of the bearing apparatus.

FIG. 6 is a top view of the bearing apparatus; and,

FIG. 7 is a bottom view of the bearing apparatus.

1 Claim, 7 Drawing Sheets
